DESIGN FOR A COMBINED FLOWERPOT AND SUPPORT

Clarence W. Jorgensen, Chicago, Ill.

Application March 8, 1941, Serial No. 99,437

Term of patent 7 years

To all whom it may concern:

Be it known that I, Clarence W. Jorgensen, a citizen of the United States, residing at Chicago, in the county of Cook and State of Illinois, have invented a new, original, and ornamental Design for a Combined Flowerpot and Support, of which the following is a specification, reference being had to the accompanying drawing, forming a part thereof.

In the drawing the figure is a perspective view of a combined flowerpot and support showing my new design.

The characteristic features of my design reside in the portions shown in full lines in the drawing.

I claim:

The ornamental design for a combined flowerpot and support, substantially as shown and described.

CLARENCE W. JORGENSEN.
